DRAIN MECHANISM FOR BARREL TYPE
CONVEYING APPARATUSLeon J. Pianowski, Detroit, Mich., assignor to The
Udylite Corporation, Detroit, Mich., a corporation of
DelawareFiled Apr. 24, 1961, Ser. No. 105,045
11 Claims. (Cl. 134—46)

The present invention broadly relates to conveying apparatus and more particularly to a barrel-type conveying machine for conveying a plurality of workpieces through a series of liquid treating stations. More specifically, the present invention pertains to a selectively actuatable drain mechanism operable when actuated to retain the workpiece container in a position above the treating solution enabling rotation of the container and tumbling of the workpieces therein to facilitate substantially complete drainage of any treating solution therein thereby minimizing solution drag-out and drag-in and contamination of succeeding treating solutions.

Because of the difficulty and commercial impracticability of handling relatively small workpieces individually during their processing through a series of treating stations it is conventional to treat such relatively small workpieces in bulk by employing a treating mechanism having barrel-like containers in which the workpieces are placed and transported therein through the prescribed treating sequence. The containers are conventionally of a porous or perforated construction to enable the treating solutions to enter and contact the workpieces therein as the containers are sequentially conveyed through the treating stations. Because of the construction of these workpiece containers, the problem is presented of achieving adequate drainage of the containers after each treating step. This problem is aggravated when the workpieces in the container are cup-shaped or of a general configuration susceptible to entrapping the treating solution therebetween preventing easy drainage thereof from the workpieces through the perforated walls of the treating container.

Inadequate drainage of the workpiece container and entrapment of liquid solution in the workpieces causes excessive "drag-out" resulting in excessive depletion of one treating solution and subsequent excessive contamination of the next successive treating solution in which the inadequately drained workpiece container is immersed. The net result of the excessive drag-out and drag-in of treating solutions is a reduction in the quality of the surface treatment obtained on the workpieces. Also of importance is the cost of replacement of the contaminated treating solutions and the loss of operating efficiency resulting from periodic shutdowns to enable replacement or replenishment of the contaminated treating solutions.

It is, accordingly, a primary object of the present invention to provide a drain mechanism for barrel-type conveying apparatus whereby substantially complete drainage is effected from the workpiece container substantially reducing the amount of drag-out and drag-in of treating solution between successive treating stations.

Another object of the present invention is to provide a drain mechanism for barrel-type conveying apparatus whereby the workpiece container on withdrawal from a treating solution is retained and rotated above the treating solution level for a predetermined time period so as to effect a tumbling of the workpieces therein minimizing entrapment of any treating solution therein.

Still another object of the present invention is to provide a drain mechanism for a barrel-type conveying apparatus wherein substantially complete drainage of the treating solution from the workpieces and workpiece container can be achieved more rapidly than heretofore pos-

2

sible thereby greatly improving the operating efficiency of the conveying apparatus.

A further objective of the present invention is to provide a barrel-drain mechanism for a barrel type conveying apparatus which is selectively operable to engage and support the workpiece container in a drain position in which the work container is rotated facilitating drainage of the treating solution therefrom and which drainage mechanism is of simple design, of durable operation, and which can be simply coordinated with the automatic operating sequence of the conveying machine.

The foregoing and other objects and advantages of the present invention are achieved by incorporating a stop mechanism on a conveying machine which is selectively actuatable and movable to and from an operative position and an inoperative position and when in said operative position is effective to engage the movable frame on which the workpiece container is rotatably mounted during the descending movement thereof whereby the barrel is supported in a drain position intermediate of the raised position and the lowered position and above the liquid level of the treating solution therebelow and in which position the barrel is rotated and the workpieces therein are tumbled so as to enable the escape and drainage of any liquid solution entrapped therein.

Other objects and advantages of the present invention will become apparent from the following detailed description taken in conjunction with the accompanying drawing, wherein:

FIGURE 1 is a plan view of a typical conveying machine to which the present invention is applicable;

FIG. 2 is a front elevation view of a barrel-type work carrier movably mounted on the conveying machine shown in FIGURE 1.

FIG. 3 is a fragmentary transverse vertical sectional view of the conveying machine shown in FIGURE 1 and including a side elevation view of the barrel-type work carrier shown in FIGURE 2;

FIG. 4 is a fragmentary plan view partly in section with parts removed for clarity illustrating the disposition of the barrel drain mechanism relative to the work carriers positioned at each treating station, and

FIGS. 5 and 6 are schematic wiring diagrams of the control circuit of the conveying machine.

Referring now in detail to the drawings and as may be best seen in FIGURES 1 to 3, a typical conveying machine to which the drain mechanism comprising the present invention is applicable comprises a central frame 10 including a series of transverse cross members 12 on which an overhead monorail 14 is rigidly secured at the outer end portions thereof. The machine as shown is of the turn-around type wherein the monorail 14 extends in a continuous loop above the treating stations and comprises a pair of straight side sections joined at each of their ends by arcuate turn-around rail sections. A machine of this general type is fully disclosed in copending United States patent application Serial No. 788,885, filed January 26, 1959, and assigned to the same assignee as the present invention. Reference is made to the aforementioned patent application for additional specific details of the construction and operation of the present conveying machine.

A plurality of work carriers 16 of the type shown in FIGURES 2 and 3 are movably mounted on the monorail 14 and are intermittently advanced therealong by an advancing mechanism such as, for example, by a reciprocable pusher mechanism 18 as may be best seen in FIGURE 3 which is mounted longitudinally of the monorail 14. The pusher mechanism 18 comprises a pair of longitudinally reciprocable pusher bars 20 having a T-shaped cross section which are slidably mounted in a series of guide shoes 22 affixed to the lower side of the cross

members 12 and extend longitudinally along the straight side portions of the machine. The pusher bars 20 are provided with a plurality of pivotally mounted pushers 24 which are adapted to engage an engaging arm 26 on each of the work carriers 16 during the advancing movement thereof whereby the work carriers are advanced along the monorail 14. The pivotally mounted pusher 24 is constructed so as to pivot during the retracting movement of the pusher bar 20 when it comes in contact with the engaging arm 26 whereby the pusher is pivoted upwardly and across the engaging arm and thereafter drops down behind the engaging arm preparatory to the next advancing movement of the pusher bar. Suitable stop means are incorporated in the pusher which is adapted to engage the depending web of the pusher bar to prevent pivoting movement thereof during the advancing motion of the pusher bar 20. It will be understood that alternate advancing mechanisms such as an intermittently driven continuous chain, for example, can be employed for advancing the work carriers 16 along the 20 monorail 14.

Advancement of the work carriers 16 along the arcuate end portions of the monorail 14 is achieved by a sector plate 28 rotatably mounted at substantially the center of curvature of each of the arcuate end sections of the machine and is provided with a series of pushers 24 thereon of the same type as employed on the pusher bars 20. The sector plate 28 is connected to the pusher bar 20 by suitable linkage arms 30 whereby the reciprocating movement of the pusher bar is transmitted to the sector plate 28 causing oscillating movement thereof in response to the reciprocating movement of the pusher bar. Movement of the pusher bar to and from a retracted position to an advanced position and concurrent oscillation of each of the sector plates 28 is accomplished by a double acting 35 fluid actuated cylinder such as a transfer cylinder 32 having the rod end thereof connected to a lever arm 34 which is connected to one of the pusher bars 20 as may be best seen in FIGURE 1. Accordingly, as the piston rod of the transfer cylinder 32 moves to and from a retracted position to an advanced position, the pusher bars 20 and the sector plates 28 connected thereto, are caused to reciprocate and oscillate, respectively, to and from a retracted position and an advanced position.

The reciprocating movement of the pusher bars and the oscillating movement of the sector plates are directionally controlled by a transfer directional signal limit switch LS21 which is mounted adjacent to the pusher bar as shown in FIGURES 1 and 3 and which is adapted to be tripped by actuators 36a, 36b when the pusher bar attains the fully advanced and fully retracted positions, respectively. The actuators 36a and 36b are adjustably secured to the web of the pusher bar 20. Actuation of the transfer directional signal limit switch LS21 by the actuators 36a, 36b, is communicated to the central control system of the conveying machine in accordance with the control circuits schematically shown in FIGS. 5 and 6 which will be subsequently described in detail.

A typical work carrier 16 is illustrated in FIGS. 2 and 3 which is employed for conveying bulk quantities of relatively small workpieces through a prescribed treating sequence. The work carrier 16 is comprised of a supporting frame 38 of an inverted U-shaped configuration which is movably mounted on the monorail 14 by means of a pair of trolleys 40 pivotally mounted to the upper horizontal member thereon and including a series of rollers 42 which are disposed in rolling bearing contact with the horizontal flange of the monorail. A hanger frame 44 is movably mounted on the supporting frame 38 and is movable thereon to and from a raised position and a lowered position. A workpiece container or barrel 46 in which a plurality of workpieces are placed and are carried therein through a prescribed treating sequence is rotatably mounted on the lower end portion of the hanger frame 44. The barrel 46 employs a porous or perforated

wall construction to enable entry and drainage of the treating solution from the interior of the barrel and assuring intimate surface contact of the solution with the workpieces contained therein.

5 The hanger frame 44 and barrel 46 rotatably mounted thereon are moved to and from the raised position and the lowered position by means of the coaction between a pinion gear 48 on each end of a transverse shaft 50 rotatably mounted on the hanger frame and which pinion gears are adapted to coact with a gear rack 52 affixed to each of the upright side portions of the supporting frame 38. Rotation of the transverse shaft 50 is achieved by reversible power means including a reversible electric motor 54 secured to a transverse member 55 of the hanger frame 44 which is drivingly connected to a suitable gear reducer 56 having a double output shaft one end of which is drivingly connected to a chain 58 which is trained over a sprocket of an overrunning coupling 60 mounted on the transverse shaft 50. The other end of the speed reducer output shaft is provided with a gear 62 which is disposed in constant meshing relationship with an idler gear 64 rotatably mounted on the hanger frame and which in turn is disposed in constant meshing relationship with a driven gear 66 affixed to the side of the barrel 46 for rotation thereof in response to energization of the reversible electric motor 54.

25 With the reversible drive mechanism illustrated, energization of the reversible electric motor is effective to control both upward and downward movement of the hanger frame and barrel thereon and concurrently provides for rotation of the barrel during the ascending and descending movement thereof and while in the lowered position. This operation is provided by the reversible characteristics of the electric motor 54 and the overrunning characteristics of the overrunning coupling 60. Accordingly, by driving the electric motor 54 in one direction which in turn drives the overrunning coupling 60 in one direction, the coupling locks up so as to engage the shaft 50 causing the hanger frame and barrel thereon to move upwardly through the coaction between the pinion gears 48 and the gear racks 52. During the descending movement of the hanger frame and barrel, the electric motor 54 is rotated in the opposite direction whereby the speed of the downward gravity-actuated movement of the hanger frame and barrel is controlled by the speed of rotation of the transverse shaft 50 which in turn is restricted from rotating faster than the housing of the coupling 60 which is drivingly connected to the gear reducer 56.

30 When the fully lowered position is attained wherein the barrel is disposed in a treating receptacle, a pair of stops 68 on the hanger frame 44 mutually engage a pair of projections 70 at the lower end of the side members of the supporting frame 38 as shown in FIG. 2 stopping the descending movement of the hanger frame and barrel. 35 Thereafter continued barrel rotation is permitted by the overrunning characteristics of the coupling 60 for a predetermined time period to enable sufficient treatment of the workpieces contained therein and on the expiration of which the direction of rotation of the reversible electric motor 54 is reversed whereby the overrunning coupling 60 engages or locks up driving the transverse shaft 50 whereby the hanger frame moves upwardly from the lowered position to the raised position. The upward travel limit of the hanger frame 44 is limited by actuation 40 of an up-travel limit switch such as limit switch LS2B illustrated in FIG. 2, which is interlocked with the central control circuit causing deenergization of the electric motor 54. Up-travel limit switches are provided at each treating station wherein the barrel is moved upwardly from the lowered position. Each of the up-travel limit switches is provided with an actuator rod 72 as shown in FIG. 2, which is movable to and from an unactuated position as shown in solid lines to an actuated position as shown in phantom by a cam member 74 secured to the hanger frame 44 and disposed in vertical alignment therewith. The

hanger frame and barrel are retained in the raised position by means of a self-locking worm wheel feature embodied in the gear reducer unit 56.

Electrical energy is supplied to the reversible drive mechanism of each of the work carriers 16 by means of a stationary contactor 76 including contacts 77 disposed at each treating station and supported on the central frame 10 by means of a series of hanger brackets 78 rigidly affixed thereto. The contacts 77 of the stationary contactor 76 are disposed so as to electrically contact the pickup brushes 81a of pickup switch 80 mounted on the supporting frame 38 of each of the work carriers 16 when each of the work carriers are appropriately positioned at each treating station. Energization of the contacts of the stationary contactors 64 is controlled in accordance with the central control system of the conveying machine as will be subsequently described in detail. In the exemplary conveying machine illustrated, the stationary contactor 76 and pickup switch 80 are provided with three contacts 77 and brushes 81, respectively, to supply 3-phase alternating current to the electric motor 54 mounted on the hanger frame.

In order to supply electrical current to the workpieces contained in the barrel 46 at such stations wherein electroplating operations, for example, are to be performed thereon, each work carrier is provided with a conductor 82 which extends downwardly along the side members of the hanger frame 44 and from there inwardly into the interior of the barrel through the barrel mounting bearing so as to contact the workpieces therein. The upper end of the conductor 82 is electrically connected to a resiliently biased contact shoe 84 which is supported on the supporting frame 38 and which is adapted to electrically engage a bus bar 86 disposed at those stations at which an electroplating operation is to be performed.

In the exemplary conveying machine shown in FIGURE 1, a total of 20 treating stations are provided which are generally designated at S-1 to S-20. The workpieces are loaded into the barrels 46 of the work carriers at the loading station S-1 and are thereafter transferred in the direction of the arrows as shown in FIGURE 1 through a series of single station treating receptacles 88 located at stations S-2 through S-7 wherein a preliminary cleaning phase, for example, is accomplished on the workpieces. Thereafter, the workpieces are conveyed by the work carriers through a multiple station treating receptacle 90 comprising stations S-8 to S-13 through which the barrels and workpieces therein are sequentially advanced while in the lowered position. When the work carriers reach the last station S-13 of the multiple station treating receptacle 90, the barrel 46 is raised and is thereafter transferred through an adjoining series of single station treating receptacles 88 located at treating stations S-14 to S-19. As the barrels are conveyed through the treating sequence, the up and down movement thereof is communicated to the central control system by means of the barrel up-travel limit switches LS1B to LS7B and LS13B to LS20B located at treating stations S-1 to S-7 and S-13 to S-20, respectively, wherein an elevating movement of the barrel is achieved. At the completion of the entire treating sequence, the workpieces are unloaded at the unload station S-20 disposed adjacent to the load station S-1.

It will be apparent from the foregoing operating sequence that during the transfer of the barrel 46 from one single station treating receptacle 88 to the next adjoining treating receptacle, the barrel must first be moved from a lowered position to a raised position and thereafter transferred above the intervening tank partitions. The barrel thereafter is lowered from the raised position to the lowered position whereby the workpieces are immersed in the treating solution contained therein. This operation presents the problem of drag-out of treating solution during the ascending movement of the barrel and drag-in of treating solution to the next adjoining treating receptacle causing a loss of expensive treating solution and a contamination of the treating solution contained in the adjoining treating receptacle. The drain mechanism comprising the present invention minimizes or substantially eliminates any drag-out and drag-in problems thereby minimizing treating solution waste, contamination, and depletion and concurrently provides for more efficient and superior surface treatments of the workpieces contained in the barrels.

The drain mechanism comprising the present invention can be best described with reference to FIGS. 3 and 4. As shown in these drawings, the drain mechanism comprises a longitudinally reciprocable angle-iron slide member 92 disposed along each of the straight side sections of the conveying machine which are connected at their ends to an arcuate section 94 pivotally connected by means of a link 96. A series of engaging shoes 98 are slidably mounted on the upper flange of an I-beam member 100 extending in a continuous loop around the machine adjacent to the monorail 14. The I-beam member 100 is supported by means of a series of braces 102 fixedly secured to the upright columns of the central frame 10. The lower portion of the I-beam member 100 can be employed for supporting the bus bar 86 as shown in FIG. 3 to supply electrical energy to the workpieces contained in the barrel.

Each of the engaging shoes 98 are secured to the longitudinally reciprocable slide members 92 and arcuate sections 94 and are reciprocable thereby to and from an operative position and an inoperative position. Reciprocation of the engaging shoes 98 is achieved by a double-acting fluid actuated cylinder, for example, such as cylinder 104 having the closed end thereof mounted on the central frame and the rod end thereof adjustably connected to an ear 106 extending from and connected to one of the slide members 92. Accordingly, the reciprocating movement of the actuating cylinder 104 is transmitted to the slide member on each side of the machine and the arcuate sections 94 pivotally connected thereto for moving the engaging shoes 98 in unison to and from an operative position and an inoperative position.

The engaging shoes 98 when disposed in the operative position are adapted to engage a rearwardly extending member 108 affixed to the hanger frame 44 of each of the work carriers for halting the gravity actuated descending movement thereof at a drain position intermediate of the raised position and the lowered position wherein the barrel 46 is disposed above the solution level in a treating receptacle therebelow. When the hanger frames and barrels are in the drain position the actuator rods 72 connected to the up-travel limit switches are released by the cam members 74. The barrel, when in the intermediate or drain position, is rotated by the reversible drive mechanism as enabled by the overrunning coupling incorporated therein whereby the workpieces in the barrel 46 are tumbled so as to enable substantially complete escape of any treating solution entrapped therein. The duration of rotation of the barrel in the drain position can be controlled by a suitable drain dwell timer incorporated in the central control system to achieve a desired drain period to assure substantially complete drainage of the treating solution from the barrel. At the expiration of this predetermined drain dwell period, the direction of rotation of the reversible electric motor 54 is reversed whereby the barrel is again elevated to the raised position preparatory to transfer to the next adjoining treating receptacle.

The engaging shoes 98 when in the inoperative position are disposed out of alignment with the engaging members 108 on the work carriers enabling unrestricted downward movement of the barrel to the fully lowered position. The movement of the engaging shoes 98 to and from the operative position and inoperative position is communicated to the central control system by means of a limit switch LS21 stationarily mounted on the central frame as shown in FIG. 4 which is adapted to be tripped by actuator

tors 110a, 110b when the fully advanced or operative position, and fully retracted or inoperative position are attained, respectively.

The movement of the engaging shoes 98 to and from the operative position and inoperative position is automatically coordinated with the ascending and descending movement of the hanger frame and barrels thereon and the advancing movement of the work carriers by means of the central control system. The engaging shoes are preferably removably attached to the slide members 92 and arcuate sections 94 whereby they can be detached therefrom and inactivated at any desired station so as to readily accommodate any desired arrangement of the treating receptacles. In accordance with the practice of the present invention, an engaging shoe 98 is provided at each station wherein the barrel 46 is withdrawn from a treating receptacle such as stations S-2 to S-7 and S-13 to S-19. Inasmuch as the barrels remain in the lowered position in the multiple station treating receptacle 90 engaging shoes are not required at stations S-8 to S-12. Similarly, engaging shoes are ordinarily not necessary at the load station S-1 and unload station S-20 which may be provided with manually operated controls to enable convenient loading and unloading of the workpieces in the barrel.

The integration of the barrel drain mechanism with the normal machine operation as previously described, provides a processing cycle commencing with the loading of the workpieces in a rotatable barrel at the load station and thereafter transferring the loaded barrel while in the elevated position to the first treating station. The barrel is thereafter lowered and rotated into a liquid treating station and maintained therein for a preselected treatment period. At the expiration of the prescribed treatment period, the barrel is raised to the fully elevated position after which the drain mechanism is actuated. Thereafter, the barrel is again lowered to an intermediate drain position where it is retained and rotated to drain substantially all of the treating solution therefrom. At the completion of a prescribed drain period, the barrel again is raised to the fully elevated position after which the pusher bar is actuated effecting the transfer of the barrel to the next adjacent treating station.

A typical operating sequence of the exemplary conveying machine shown in FIGURE 1 provided with a barrel drain mechanism in accordance with the preferred embodiments of the present invention, will now be described with particular reference to the central control system as diagrammatically shown in FIGS. 5 and 6. The wiring diagrams of FIGS. 5 and 6 comprise a single circuit wherein the wiring diagram of FIG. 5 is electrically connected to the wiring diagram of FIG. 6 at junctions X1—X1, Y1—Y1, and Z1—Z1, respectively. To facilitate identification of the components in the electrical circuit shown in the drawings, motor control relays are designated as CM; control relays are designated as CR, and latch relays are designated as LU with their close or latch coils indicated with a "C" and their trip coil indicated with a "T".

The individual wiring circuit of the reversible drive mechanism of each of the work carriers is schematically shown in FIG. 5, of which the carrier at station S-1 is typical. The circuit includes the reversible electric motor 54 which is electrically connected by conductors 112, 114 and 116 to the manually operable contacts SW-1, SW-2, and SW-3, of a manually operated switch 118 mounted on the supporting frame 38 of the work carrier as may be best seen in FIG. 2 within convenient access of the machine operator. The contacts SW-1, SW-2, and SW-3 of the manual switch 118 are electrically connected to the brushes 81 of the pickup switch 80 which in turn are adapted to be disposed in electrical contact with the contacts 77 of the stationary contactor 76. The contacts 77 of the stationary contactor 76 are in turn electrically connected to suitable motor overloads and thence

to motor control contacts which are operable in response to energization of motor control relays CM1 to CM20 as shown in FIG. 6.

The contacts 77 of the stationary contactors 76 of stations S-1 to S-7 and S-13 to S-20 are electrically connected to conductors L1A, L2A, and L3A which is provided with line-reversing contacts CR3U-4 and CR3D-4 for reversing the direction of rotation of the reversible electric motors at those stations to achieve the appropriate ascending and descending movement of the hanger frames and barrels thereon. The contacts 77 of the stationary contactor 76 at stations S-8 to S-12 are electrically connected to conductors L1B, L2B and L3B, having no reversing contacts therein inasmuch as the barrels at stations S-9 to S-12 remain in the lowered position and are merely rotated in that position during their advancement through the multiple station treating receptacle 90 as shown in FIGURE 1. The barrel at station S-8 is only lowered from the raised position to the lowered position and no reversing electric current is required.

The operating cycle of the conveying machine will now be described commencing with the position wherein the work carriers 16 and the barrels thereon are in the full raised position at treating stations S-1 to S-7 and S-13 to S-20, and are in the fully lowered position at stations S-8 to S-12. In this position the up-travel signal limit switches LS1B to LS7B and LS13B to LS20B are actuated by the cam member 74 on each of the work carriers. The transfer cylinder 32 and the pusher mechanism are in the fully retracted position and the transfer directional signal limit switch LS21 is fully actuated by actuator 32b and the engaging shoes 98 are disposed in the retracted or inoperative position whereby the limit switch LS22 is actuated by actuator 110b.

The machine is energized by closing the main disconnect switch 120 whereby electrical current flows through conductors L1, L2 and L3, energizing a control transformer 122 supplying current to the control circuit. Push-button start switch 124 is depressed energizing motor control relay CM21 which on energization closes its holding contact CM21-1 enabling the start switch 124 to be released and simultaneously closes its contacts CM21-2 energizing the hydraulic pump motor 126 whereby a flow of pressurized fluid commences in the machine hydraulic system. The control circuit push-button starter switch 128 is next depressed energizing control relay CR1 which closes its holding contact CR1-1 enabling the start button 128 to be released and closes its contacts CR1-2 and CR1-3 energizing the control circuit of the machine. The hydraulic motor circuit and the machine control circuit can be deenergized by depressing stop push-button switches 130 and 132, respectively.

At the instant that the control circuit of the machine is energized, the close of coil of the barrel-up signal latch relay LU1 is energized through transfer directional signal limit switch contact LS21-1 and barrel-up travel limit switch series contacts LS1B-1 to LS7B-1 and LS13B-1 to LS20B-1 and normally closed contact LU2-1. On energization of the close coil of latch relay LU1, its normally open contacts LU1-1, LU1-2 and LU1-4 close and its normally closed contacts LU1-3, LU1-5, and LU1-6 contacts open. The closing of contact LU1-1 energizes the drain mechanism forward control relay CR8 through contacts LU1-1, CR3U-1, CR3D-1, CR7-1, and LU3-1. Energization of control relay CR8 causes its normally open contact CR8-1 to close energizing forward solenoid LA whereby pressurized fluid is directed into the blank end of the transfer cylinder 104 whereby the slide member and engaging shoes thereon commence their advancing movement from the inoperative position to the operative position. At the completion of the forward movement of the slide member, directional signal limit switch LS22 is operated by actuator 110a closing its contacts

LS22-1 and LS22-3 and opening its contacts LS22-2 and LS22-4.

The closing of contact LS22-1 causes the close coil of drain mechanism forward signal latch relay LU3 to be energized through contacts LU1-1, CR3U-1, CR3D-1, CR7-1, and LS22-1 which in turn closes its normally open contacts LU3-2 and LU3-3 and opens its normally closed contacts LU3-1 and LU3-4. The closing of contact LU3-3 causes the closed coil of travel directional signal latch relay LU2 to be energized through contacts LU3-3, LU1-2, and LU4-1. Latch relay LU2 closes its normally open contact LU2-2 and opens its normally closed contacts LU2-1 and LU2-3. The closing of contact LU2-2 energizes the down coil CR3D of line reversing contactor which closes its normally open contacts CR3D-3, CR3D-4 and CR3D-5 and opens its normally closed contacts CR3D-1 and CR3D-2. Simultaneously, down signal control relays CR5 and CR6 are energized through contact LU2-2 which close their contacts CR5-1 to CR5-8 and CR6-1 to CR6-7, respectively, thereby energizing motor control relays CM1 and CM7 and CM13 to CM20 which in turn close their corresponding motor control contacts CM1-1 to CM7-1 and CM13-1 to CM20-1, respectively.

The instant that line reversing contacts CR3D-4 are closed, electrical energy is supplied to the reversible electric motors of the work carriers positioned at stations S-1 to S-7 and S-13 to S-20 whereby they commence their downward movement. The reversible electric motors of the work carriers at stations S-8 to S-12 are energized on the closing of contact CR3D-5, energizing their respective motor control relays CM8 to CM12 which in turn close their respective contacts CM8-1 to CM12-1 whereby the barrels of these work carriers commence to rotate while in the lowered position.

As the barrels at stations S-1 to S-7 and S-13 to S-20 descend, barrel-up signal limit switches at these stations are released closing their contacts LS1B to LS7B and LS13B to LS20B and opening their contacts LS1B-1 to LS7B-1 and LS13B-1 to LS20B-1. The barrels continue their descending movement until the engaging member 108 on the hanger frame of the work carriers engages the engaging shoe 98 of the barrel drain mechanism whereby the barrels are halted in a drain position above the treating solution in the treating receptacle therebelow and the barrels continue to rotate tumbling the work-pieces therein thereby facilitating drainage of any entrapped treating solution.

The duration of the drain cycle is controlled by a suitable drain-dwell timer TR1 which is energized through contacts LU1-3 and LS22-3, the instant the trip coil of latch relay LU1 is energized on the closing of contact LU2-2. The tripping of latch relay LU1 also deenergizes drain mechanism forward control relay CR8 through contact LU1-1 which opens its contact CR8-1 deenergizing forward solenoid valve LA. It is conventional for the drain dwell timer TR1 to be set for a dwell period substantially shorter than that of the down dwell timer TR2 which is employed for controlling a predetermined down-dwell treating period of the workpieces when in the fully lowered position. Accordingly, while both the down-dwell timer TR2 and the drain dwell timer TR1 are energized on the closing of normally closed contacts LU1-3, the shorter timing duration of the drain dwell timer TR1 controls the drain portion of the cycle.

Energization of the drain dwell timer TR1 causes it to close its normally open contact TR1-1. At the expiration of a predetermined drain dwell period, the drain dwell timer TR1 closes its normally open contact TR1-2 energizing the trip coil of travel directional latch relay LU2 causing it to become unlatched thereby closing its normally closed contacts LU2-1 and LU2-3 and opening its normally open contact LU2-2. The opening of normally open contact LU2-2 deenergizes down signal

control relays CR5 and CR6 which open their contacts CR5-1 to CR5-8 and CR6-1 to CR6-7, respectively. Simultaneously, the down coil CR3D of the line reversing contactor is deenergized closing its normally closed contacts CR3D-1 and CR3D-2 and opening its normally open contacts CR3D-3, CR3D-4, and CR3D-5. The opening of line reversing contact CR3D-4 deenergizes the reversible motors of the work carriers at stations S-1 to S-7 and S-13 to S-20. Simultaneously, the reversible electric motors of the work carriers positioned at stations S-8 to S-12 are deenergized by the opening of contact CR3D-5, deenergizing their respective motor control relays CM8 to CM12 which in turn open their respective contacts CM8-1 to CM12-1.

The closing of contact CR3D-2 energizes line reversing contactor up coil CR3U through contacts LS21-1, LU1-5, LU2-3, and CR3D-2 which in turn closes its normally open contacts CR3U-2, CR3U-4, and CR3U-5 and opens its normally closed contacts CR3U-1 and CR3U-3. The closing of line reversing contacts CR3U-4 supplies reversing electric current to the reversible electric motors of the work carriers positioned at stations S-1 to S-7 and S-13 to S-20 which commence their elevating movement from the drain position to the raised position. Simultaneously, the closing of contact CR3U-5 reenergizes motor control relays CM8 to CM12 which close their respective contacts energizing the reversible electric motors of the work carriers at stations S-8 to S-12, which commence to rotate in the same direction remaining in the lowered position. The closing of contact CR3U-2 energizes the close coil of drain cycle latch relay LU4 through contacts LU3-2 and CR3U-2 which opens its normally closed contact LU4-1 and closes its normally open contacts LU4-2 through LU4-4.

When the barrels at stations S-1 to S-7 and S-13 to S-20 attain the fully raised position, barrel-up travel signal limit switches LS1B to LS7B and LS13B to LS20B are actuated opening their contacts LS1B to LS7B and LS13B to LS20B deenergizing the motor control relays at these stations which open their respective contacts deenergizing the reversible electric motors of the work carriers at these stations. At the same time, actuation of the barrel-up travel signal limit switches causes their series contacts LS1B-1 to LS7B-1 and LS13B-1 to LS20B-1 to close whereby the close coil of barrel-up signal switch relay LU1 is energized through the series contacts and LU2-1. Energization of the close coil of latch relay LU1 causes it to close its normal open contacts LU1-1, LU1-2, LU1-4 and open its normally close contacts LU1-3, LU1-5, and LU1-6.

Latching of latch relay LU1 causes its contact LU1-5 to open deenergizing the up coil CR3U of the line reversing contactor which closes its normally closed contacts CR3U-1 and CR3U-3 and opens its normally open contacts CR3U-2, CR3U-4 and CR3U-5. The opening of line reversing contacts CR3U-4 removes electrical power from the line side of motor control contacts at stations S-1 to S-7 and S-13 to S-20. Simultaneously, the opening of contact CR3U-5 deenergizes motor control relays CM8 to CM12 which open their respective contacts removing energy from the stationary contactor at stations S-8 to S-12.

Drain mechanism return control relay CR9 is energized through contacts LU1-1, CR3U-1, CR3D-1, CR7-1, LS21-1, LU1-4 and LU4-2 contacts which in turn closes its contact CR9-1 energizing return solenoid LB whereby pressurized fluid is directed into the rod end of the cylinder 104 whereby the slide member and engaging shoes 98 thereon commence their retracting movement. When the retracted position is attained wherein the engaging shoes 98 are disposed in the inoperative position, directional signal limit switch LS22 is actuated by actuator 110b which closes its contacts LS22-2 and LS22-4 and opens its contacts LS22-1 and LS22-3. The opening of contact LS22-1 deenergizes drain mechanism return con-

trol relay CR9 which opens its contacts CR9-1, deenergizing return solenoid LB. Simultaneously, transfer forward signal control relay CR2 is energized through contacts LU1-1, CR3U-1, CR3D-1, CR7-1, LS22-2, and LU4-4, which in turn opens its normally closed contact CR2-1 and closes its normally open contact CR2-2 energizing forward transfer solenoid KA enabling pressurized fluid to flow into the blank end of the transfer cylinder 32 whereby the pusher mechanism commences its advancing movement and the work carriers and barrels thereon which are substantially free of any drag-out treating solution, are advanced to the next adjoining treating station.

As the pusher mechanism approaches the fully advanced position, transfer directional signal limit switch LS21 is actuated by actuator 36a which opens its contact LS21-1 and closes its contact LS21-2. The closing of contact LS21-2 energizes the close coil of travel directional signal latch relay LU2 which opens its normally closed contacts LU2-1 and LU2-3 and closes its normally open contact LU2-2. The closing of contact LU2-2 energizes the down coil CR3D of the line reversing contactor through contacts LU2-2 and CR3U-3, which in turn opens its normally closed contacts CR3D-1 and CR3D-2 and closes its normally open contacts CR3D-3, CR3D-4, and CR3D-5. Simultaneously, the trip coil of latch relay LU1 is energized through contact LU2-2 which opens its normally open contacts LU1-1, LU1-2, and LU1-4 and closes its normally closed contacts LU1-3, LU1-5 and LU1-6. The closing of contact LU1-3 energizes the down dwell timer TR2, closes its contact TR2-1 and commences to time a predetermined down dwell period. The trip coil of drain mechanism forward signal latch relay LU3 is energized through contacts CR3D-3 and LU4-3 which in turn closes its contact LU3-4 energizing the trip coil of drain cycle latch relay LU4 through contact CR3D-3. Latch relays LU3 and LU4 return to their normal unlatched position. Transfer forward control relay CR2 is deenergized on the opening of contact CR3D-1 which opens its contact CR2-2, deenergizing the forward solenoid KA and closes its normally closed contact CR2-1.

Electrical energy is supplied to down signal control relays CR5 and CR6 through contact LU2-2 which in turn close their respective contacts CR5-1 to CR5-8 and CR6-1 to CR6-7 energizing their respective motor control relays which in turn close their contacts CM1-1 to CM7-1 and CM13-1 to CM20-1. Energization of the reversible electric motors occurs on the closing of line reversing contacts CR3D-4 wherein electric power is supplied to the work carriers at stations S-1 to S-7 and S-13 to S-20. The carriers at these stations with the exception of station S-13, wherein the carrier is already in the lowered position, commence their descending movement. The barrels of the work carriers at the stations S-8 to S-12 are energized on the closing of contact CR3D-5 wherein the barrel at station S-8 commences its downward movement and the barrels at stations S-9 to S-12 commence to rotate while in the lowered position.

As the barrels descend, barrel-up travel limit switches LS1B to LS7B and LS14B to LS20B are released closing their respective contacts LS1B to LS7B and LS14B to LS20B. When the pusher mechanism attains the fully retracted position travel directional signal limit switch LS21 is actuated by actuator 36b opening its contact LS21-2 and closing its contact LS21-1. Opening of contact LS21-2 deenergizes transfer return control relay CR7 which opens its normally open contact CR7-2, deenergizing return solenoid KB.

When the barrels at stations S-1 to S-8 and S-14 to S-20 attain the fully lowered position they continue to rotate in that position along with the barrels at stations S-9 to S-13 which were retained in the lowered position. Upon the expiration of a predetermined down dwell period as timed by the down dwell timer TR2, its contact

TR2-2 closes energizing the trip coil of travel directional signal latch relay LU2 through contacts LS21-1, TR2-1 and TR2-2. Latch relay LU2 becomes unlatched, opening its contact LU2-2 and closing its contacts LU2-1 and LU2-3. The opening of contact LU2-2 deenergizes down signal control relays CR5 and CR6 which open their contacts CR5-1 to CR5-8 and CR6-1 to CR6-7, respectively. Simultaneously, the down coil CR3D of line reversing contactor is deenergized on the opening of contact LU2-2 which in turn opens its contacts CR3D-3 through CR3D-5 and closes its contacts CR3D-1 and CR3D-2.

The opening of contact CR3D-5 deenergizes motor control relays CM8 to CM12 at stations S-8 to S-12 whereby the barrels at these stations cease to rotate. Simultaneously, line reversing contacts CR3D-4 are open, deenergizing the stationary contactor at stations S-1 to S-7 and S-13 to S-20. The closing of contact CR3D-2 energizes the up coil CR3U of the line reversing contactor through contacts LS21-1, LU1-5 and LU2-3, which in turn closes its contacts CR2U-2, CR3U-4 and CR3U-5 and opens its contacts CR3U-1 and CR3U-3.

The closing of contact CR3U-5 energizes the motor control relays CM8 to CM12 which close their respective contacts CM8-1 to CM12-1 whereby the barrels at stations S-8 to S-12 again commence to rotate in the same direction while in the lowered position. The closing of line reversing contacts CR3D-4 supplies reversing electrical current to the stationary contactors at stations S-1 to S-7 and S-13 to S-20 whereby the barrels commence their ascending movement.

The barrels at stations S-1 to S-7 and S-13 to S-20 continue their ascending movement until the cam member 74 on each of the work carriers contacts the actuator rod 72 of the barrel up-travel limit switches at each of these stations. Actuation of the barrel up-travel signal limit switch causes their contacts LS1B to LS7B and LS13B to LS20B to open deenergizing the motor control relays CM1 to CM7 and CM13 to CM20 which in turn open their respective contacts CM1-1 to CM7-1 and CM13-1 to CM20-1 whereby the reversible electric motors of the work carriers at these stations are deenergized with the barrels in the fully raised position. At the same time the close coil of barrel-up signal latch relay LU1 is energized through series contacts LS1B-1 to LS7B-1 and LS13B-1 to LS20B-1 and contact LU2-1 which in turn closes its contacts LU1-1, LU1-2, and LU1-4 and opens its contacts LU1-3 and LU1-5. The opening of contact LU1-5 deenergizes the up coil CR3U of the line reversing contactor which in turn closes its contacts CR3U-1 and CR3U-3, and opens its contacts CR3U-2, CR3U-4 and CR3U-5.

The barrels at stations S-2 to S-7 and S-13 to S-19 which have been raised from a lowered position in a treating receptacle to a raised position above that receptacle contain entrapped treating solutions therein which is substantially eliminated by the subsequent drain cycle prior to transfer to the next adjoining treating receptacle in accordance with the cycle hereinbefore described. As hereinbefore stated, the unload station S-20 and load station S-1 may be provided with automatic loading or unloading equipment for handling the work-pieces to be processed.

While it will be apparent that the preferred embodiments herein illustrated are well calculated to fulfill the objects above stated, it will be appreciated that the invention is susceptible to modification, variation and change without departing from the proper scope or fair meaning of the subjoined claims.

What is claimed is:

1. In a work carrier for immersing workpieces in a treating receptacle, the combination comprising a first frame, a second frame movably and guidably mounted on said first frame and including a workpiece container rotatably mounted thereon, power means on said second frame for moving said second frame and said container

thereon to and from a raised position above a treating receptacle and a lowered position wherein said container and workpieces therein are disposed in a receptacle and for concurrently rotating said container when in said lowered position and during the ascending and descending movement thereof, coacting means on said first and second frames for limiting the descending movement of said container in said lowered position, and stop means selectively actuatable for engaging said second frame and stopping the descending movement thereof at a drain position wherein said container is disposed intermediate said raised and said lowered positions and above a treating receptacle whereby drainage of the treating solution from the workpieces in said container is facilitated as said container is rotated.

2. In a work carrier for immersing workpieces in a treating receptacle, the combination comprising a first frame, a second frame movably and guidably mounted on said first frame and including a workpiece container rotatably mounted thereon, reversible drive means mounted on said second frame operative when driving in one direction for moving said second frame and said container thereon from a raised position above a treating receptacle to a lowered position wherein said container and workpieces therein are disposed in a receptacle and for concurrently rotating said container when in said lowered position and during the descending movement thereof, said drive means operable when driven in the opposite direction for moving said second frame and said container thereon from said lowered position to said raised position and for concurrently rotating said container during the ascending movement thereof, coacting means on said first and said second frames for limiting the descending movement of said container in said lowered position, and stop means selectively actuatable for engaging said second frame and stopping the descending movement thereof at a drain position wherein said container is disposed intermediate of said raised and said lowered positions and above a treating receptacle whereby drainage of the treating solution from the workpieces in said container is facilitated as said container is rotated.

3. In a work carrier for immersing workpieces in a treating receptacle, the combination comprising a first frame, a second frame movably and guidably mounted on said first frame and including a workpiece container rotatably mounted thereon, reversible drive means mounted on said second frame for moving said second frame and said container thereon to and from a raised position above a treating receptacle and a lowered position wherein said container and workpieces therein are disposed in a receptacle and for concurrently rotating said container when in said lowered position and during the ascending and descending movement thereof, said reversible drive means including shaft means rotatably mounted on said second frame, coacting means on said shaft means and said first frame for relative driving therethrough, overrunning coupling means on said shaft means drivingly connected to a reversible motor means on said second frame, means drivingly connecting said container to said motor means for rotation thereof in response to rotation of said motor means, said motor means when rotated in one direction operative to rotate said container and said shaft means and move said second frame upwardly and when rotated in the opposite direction operative in combination with said overrunning coupling means to rotate said container and for releasing said shaft means to provide for downward gravity actuated movement of said second frame, means for limiting the downward gravity actuated movement of said container when it attains said lowered position, and stop means selectively actuatable for engaging said second frame and stopping the descending gravity movement thereof at a drain position wherein said container is disposed intermediate of said raised and said lowered positions and

above a treating receptacle whereby drainage of the treating solution from the workpieces in said container is facilitated as said container is rotated.

4. In a work carrier for immersing workpieces in a treating receptacle, the combination comprising a first frame, a second frame movably and guidably mounted on said first frame and including a workpiece container rotatably mounted thereon, reversible drive means mounted on said second frame for moving said second frame and said container thereon to and from a raised position above a treating receptacle and a lowered position wherein said container and workpieces therein are disposed in a receptacle and for concurrently rotating said container when in said lowered position and during the ascending and descending movement thereof, said reversible drive means including shaft means rotatably mounted on said second frame, coacting means on said shaft means and said first frame for relative driving therethrough, overrunning coupling means on said shaft means drivingly connected to a reversible motor means on said second frame, means drivingly connecting said container to said motor means for rotation thereof in response to rotation of said motor means, said motor means when rotated in one direction operative to rotate said container and said shaft means and move said second frame upwardly and when rotated in the opposite direction operative in combination with said overrunning coupling means to rotate said container and for releasing said shaft means to provide for downward gravity actuated movement of said second frame, means for limiting the downward gravity actuated movement of said container when it attains said lowered position, and stop means movable to and from an operative position and an inoperative position for selectively engaging said second frame during the descending gravity actuated movement thereof for selectively stopping said second frame at a drain position disposed intermediate said raised and said lowered positions wherein said container is disposed above a treating receptacle facilitating the drainage of treating solution from the workpieces as said container is rotated in said drain position, means for moving said stop means to and from said operative and said inoperative positions, and control means for energizing and controlling the direction of rotation of said reversible motor means and for coordinating the movement of said stop means.

5. A conveying machine comprising a framework, a rail on said framework, a work carrier including a first frame movably mounted on said rail and a second frame guidably mounted on said first frame for up and down movement thereon, a workpiece container rotatably mounted on said second frame, power means on said second frame for moving said second frame and said container thereon to and from a raised position wherein said container is disposed above a treating receptacle to a lowered position wherein said container is disposed in the receptacle and for rotating said container while in said lowered position and during the ascending and descending movement thereof, coacting means on said first and said second frames for limiting the descending movement of said container in said lowered position, and stop means selectively actuatable for engaging said second frame and stopping the descending movement thereof at a drain position wherein said container is disposed intermediate of said raised and said lowered positions and above a treating receptacle whereby drainage of the treating solution from the workpieces in the container is facilitated as said container is rotated.

6. In a conveying machine for immersing workpieces in a treating receptacle, the combination comprising a framework, a rail on said framework, a work carrier including a first frame movably mounted on said rail and a second frame guidably mounted on said first frame for up and down movement thereon, a workpiece container rotatably mounted on said second frame, power

means on said second frame for moving said second frame and said container thereon to and from a raised position wherein said container is disposed above a treating receptacle to a lowered position wherein said container is disposed in a treating receptacle and for rotating said container when in said lowered position and during the ascending and descending movement thereof, coacting means on said first and said second frame for limiting the descending movement of said container in said lowered position, and stop means on said framework adjacent to said rail and selectively movable to and from an operative position and an inoperative position, said stop means when in said operative position disposed in engaging alignment with said second frame for engaging and stopping the descending movement thereof at a drain position disposed intermediate of said raised and said lowered positions and above a treating receptacle whereby drainage of the treating solution from the workpieces in said container is facilitated as said container is rotated, said stop means when in said inoperative position disposed out of engaging alignment with said second frame.

7. In a conveying machine for immersing workpieces in a treating receptacle, the combination comprising a framework, a rail on said framework, a work carrier including a first frame movably mounted on said rail and a second frame guidably mounted on said first frame for up and down movement thereon, a workpiece container rotatably mounted on said second frame, power means on said second frame for moving said second frame and said container thereon to and from a raised position wherein said container is disposed above a treating receptacle to a lowered position wherein said container is disposed in said receptacle and for rotating said container while in said lowered position and during the ascending and descending movement thereof, coacting means on said first and said second frames for limiting the descending movement of said container in said lowered position, and stop means on said framework disposed adjacent to said rail for selectively engaging said second frame and stopping the descending movement thereof at a drain position wherein said container is disposed intermediate said raised and said lowered positions and above a treating receptacle whereby drainage of the treating solution from the workpieces in said container is facilitated as said container is rotated, said stop means comprising a longitudinally reciprocable member on said framework, an engaging shoe on said member and reciprocable thereby to and from an operative position wherein said shoe is disposed so as to engage said second frame on the descending movement thereof and an inoperative position spaced therefrom, means for reciprocating said member, and control means for controlling said power means and the reciprocating movement of said reciprocable member.

8. In a conveying machine for immersing workpieces in a treating receptacle, the combination comprising a framework, a rail on said framework, a work carrier including a first frame movably mounted on said rail and a second frame guidably mounted on said first frame for up and down movement thereon, a workpiece container rotatably mounted on said second frame, reversible drive means mounted on said second frame operative when driving in one direction for moving said second frame and said container thereon from a raised position above a treating receptacle to a lowered position wherein said container and workpieces therein are disposed in the receptacle and for concurrently rotating said container when in said lowered position and during the descending movement thereof, said drive means operable when driven in the opposite direction for moving said frame and said container thereon from said lowered position to said raised position and for concurrently rotating said container during the ascending movement thereof, and engaging means on said first and said second frames for limiting the descending movement of said container in said lowered position, stop means on said framework

adjacent to said rail and selectively movable to and from an operative position and an inoperative position, said stop means when in said operative position disposed in engaging alignment with said second frame for engaging and stopping the descending movement thereof at a drain position disposed intermediate of said raised and said lowered positions and above a treating receptacle whereby drainage of the treating solution from the workpieces in said container is facilitated as said container is rotated, said stop means when in said inoperative position disposed out of engaging alignment with said second frame.

9. In a conveying machine for immersing workpieces in a treating receptacle, the combination comprising a framework, a rail on said framework, a work carrier including a first frame movably mounted on said rail and a second frame guidably mounted on said first frame for up and down movement thereon, a workpiece container rotatably mounted on said second frame, reversible drive means mounted on said second frame for moving said second frame and said container thereon to and from a raised position above a treating receptacle and a lowered position wherein said container and workpieces therein are disposed in a receptacle and for concurrently rotating said container when in said lowered position and during the ascending and descending movement thereof, said reversible drive means including shaft means rotatably mounted on said second frame, coacting means on said shaft means and said first frame for relative driving therethrough, overrunning coupling means on said shaft means drivingly connected to a reversible motor means on said second frame, means drivingly connecting said container to said motor means for rotation thereof in response to rotation of said motor means, said motor means when rotated in one direction operative to rotate said container and said shaft means and move said second frame upwardly and when rotated in the opposite direction operative in combination with said overrunning coupling means to rotate said container and for releasing said shaft means to provide for downward gravity actuated movement of said second frame, coacting means on said first and said second frames for limiting the downward gravity actuated movement of said container when it attains said lowered position, and stop means on said framework disposed adjacent to said rail for selectively engaging said second frame and stopping the gravity actuated descending movement thereof at a drain position wherein said container is disposed intermediate said raised and said lowered positions and above a treating receptacle whereby drainage of the treating solution from the workpieces in said container is facilitated as said container is rotated, said stop means comprising a longitudinally reciprocable member on said framework, an engaging shoe on said member and reciprocable thereby to and from an operative position wherein said shoe is disposed so as to engage said second frame on the gravity actuated descending movement thereof and an inoperative position spaced therefrom, means for reciprocating said member, and control means for controlling said reversible drive means and coordinating the reciprocating movement of said reciprocable member.

10. In a conveying machine for immersing workpieces in a series of treating receptacles the combination comprising a framework, a rail on said framework, a plurality of work carriers movably mounted on said rail, advancing means for intermittently advancing said work carriers along said rail, each of said work carriers comprising a first frame movably mounted on said rail and a second frame guideably mounted on said first frame for up and down movement thereon, a workpiece container rotatably mounted on said second frame, power means on said second frame for moving said second frame and said container thereon to and from a raised position wherein said container is disposed above a treating receptacle to a lowered position wherein said container is

disposed in a receptacle and for rotating said container while in said lowered position and during the ascending and descending movement thereof, coacting means on said first and said second frames for limiting the descending movement of said container in said lowered position, and stop means extending longitudinally of said rail and mounted on said framework and selectively actuatable for engaging said second frame of selected ones of said work carriers and stopping the descending movement thereof at a drain position wherein said containers are disposed intermediate of said raised and said lowered positions and above a treating receptacle whereby drainage of the treating solution from the workpieces in said containers is facilitated as said containers are rotated in said drain position.

11. In a work carrier for immersing workpieces in a treating receptacle, the combination comprising a supporting frame, a workpiece container movably and rotatably mounted on said supporting frame for up and down movement thereon, means for moving said container from a raised position above a treating receptacle to a lowered position in a treating receptacle, means for rotating said container while in said lowered position, means for rotat-

ing and raising said container from said lowered position to said raised position, means for lowering said container from said raised position to a drain position disposed intermediate of said raised position and said lowered position wherein said container is disposed above the treating receptacle, stop means selectively operable for supporting said container while in said drain position, means for rotating said container in said drain position thereby facilitating drainage of the treating solution from the workpieces therein, and means for rotating and raising said container from said drain position to said raised position.
